UNITED STATES PATENT OFFICE.

FRANK J. BURKLEY, OF OMAHA, NEBRASKA.

ENVELOP-FEEDER.

1,329,108.

Specification of Letters Patent. Patented Jan. 27, 1920.

Application filed July 3, 1919. Serial No. 308,367.

To all whom it may concern:

Be it known that I, FRANK J. BURKLEY, a citizen of the United States, residing at Omaha, in the county of Douglas and State 5 of Nebraska, have invented certain new and useful Improvements in Envelop-Feeders, of which the following is a specification, reference being had therein to the accompanying drawing.

10 The invention relates to feeders for feeding envelopes to printing presses, whereby the envelopes are fed one at a time and are grasped by grippers carried by the roller, said roller carrying each envelop to a printing point where the envelopes are printed.

15 A further object is to provide a feeder receptacle for envelopes which may be adjusted to receive different sizes of envelopes, also to provide said receptacle with feeding means 20 whereby the envelopes may be picked from the receptacle one at a time by the gripping members carried by the roller.

25 A further object is to provide means whereby the stack of envelopes may be inclined, thereby facilitating the feeding of the same.

30 With the above and other objects in view, the invention resides in the combination and arrangement of parts as hereinafter set forth, shown in the drawings described and claimed, it being understood that changes in the precise embodiment of the invention 35 may be made within the scope of what is claimed, without departing from the spirit of the invention.

In the drawings:—

Figure 1 is a side elevation of the receptacle showing the same supported above a printing roller.

40 Fig. 2 is a plan view of the device.

Fig. 3 is a sectional view through the receptacle and the upper portion of the feeding roller.

45 Referring to the drawings the numeral 1 designates a feed roller by means of which the envelopes are fed and conveyed to the printing point, which may be located below the roller, and 2 the gripper carried by the roller. There may be as many grippers as 50 desired and for purposes of illustration only one gripper is shown.

55 Supported on bars 3 and 4, which are disposed above the roller is an envelop receptacle 5, in which receptacle envelopes are disposed as clearly shown in Fig. 3. The envelopes having their flaps 6 downwardly dis-

posed so that as the roller revolves in the direction of the arrow *a* said flap will be engaged by the gripper 2 and conveyed to the printing point.

60

Receptacle 5 comprises the sections 7 and 8, which sections are provided with side and front walls 9 and 10, the side walls being adapted to engage the ends of the envelopes and the walls 10 are adjacent the flap edge 65 of the envelopes. Walls 10 are provided with lugs 11, which are disposed in longitudinal slots 12 of the supporting bar 3. Supporting bar 4 is also provided with a longitudinal slot 13, which slot is at right angle to slots 70, 14 in the bottoms 15 of the sections 7 and 8. Passing through slots 14 and the slot 13 are bolts 16, by means of which bolts, the sections may be adjusted closer together or farther apart, thereby allowing the use of the 75 same receptacle for different sizes of envelopes. During this adjustment the lugs 11 will move longitudinally in the slots 12. The forward edges of the bottoms 15 are cut away so that the gripper 2 may enter the 80 bottom of the sections far enough so that said gripper will engage the edge of the envelop flaps. The side walls of the sections are provided with guide flanges, whereby the 85 stack of envelopes will be prevented from becoming twisted.

Secured to the bar 4 as at 19 and disposed between the edges of the bottoms 15 of the sections 7 and 8 is a forwardly extending feed finger 21, the free end 22 of which terminates adjacent the lower end 23 of a downwardly extending spring arm 24. Arm 24 exerts a binding action on the edges 90

of the envelopes, thereby providing means whereby the envelopes will be choked and 95 prevented from feeding too fast. Adjustable longitudinally on the finger 21, by means of a lock bolt 25 is a triangular shaped envelop feed 26, the apex end of said feed being adapted to be disposed below one edge 100 of the stack of envelopes, thereby causing the edge of the envelop remote from the flap edge to be elevated so that the gripper may easily grasp the flap and pull the envelopes from the receptacle at a point between the 105 ends 22 and 23 of the finger 21 and the spring arm 24. By the inward or outward adjustment of the member 26, it will be seen that the inclination of the envelopes may be increased or diminished and the proper feed- 110 ing of the envelopes insured. It will also be seen that by the adjustable construction of

the receptacle, that it will be possible for the same to be adjusted to receive different sizes of envelops.

The invention having been set forth, what is claimed as new and useful is:—

An envelop feeder for printing presses comprising a receptacle, said receptacle being formed in sections, each section being supported in such a manner that they may be adjusted in relation to each for the reception of different sizes of envelops, the forward ends of said sections having their bottoms cut away, a spring feed finger disposed between the bottoms of each section, a downwardly extending spring feed finger between

the sections at their front ends, the ends of the feed fingers terminating adjacent each other, an inclined member disposed in the bottom of the receptacle, means for adjusting said inclined member for increasing or diminishing the inclination of the envelops and a gripper carried by said feed roller and so disposed as to enter the cut away portions of the bottoms of the sections to grasp an envelop flap and withdraw the envelop from the receptacle between the adjacent ends of the spring fingers.

In testimony whereof I hereunto affix my signature.

FRANK J. BURKLEY.
